[57] CLAIM

The ornamental design for a combined television and radio receiver and tape recorder, as shown and described.

DESCRIPTION

FIG. 1 is a front, top and right side perspective view of the combined television and radio receiver and tape recorder showing our new design;

FIG. 2 is a view like FIG. 1 with the tape recorder removed;

FIG. 3 is a top plan view thereof;

FIG. 4 is a front elevational view thereof;

FIG. 5 is a rear elevational view thereof;

FIG. 6 is a bottom plan view thereof;

FIG. 7 is a left side elevational view thereof; and

FIG. 8 is a right side elevational view thereof.
